UNITED STATES PATENT OFFICE.

FRANCIS H. TREAT, OF PITTSBURG, PENNSYLVANIA.

ТИЛТИНГ ФУРНАС.

No. 802,151.

Specification of Letters Patent.

Patented Oct. 17, 1905.

Application filed November 25, 1903. Serial No. 182,674.

To all whom it may concern:

Be it known that I, FRANCIS H. TREAT, of Pittsburgh, Allegheny county, Pennsylvania, have invented a new and useful Tilting Furnace, of which the following is a full, clear, and exact description, reference being had to the accompanying drawings, forming part of this specification, in which—

Figure 1 is a vertical cross-section of my improved furnace. Fig. 2 is a partial side elevation, partly broken away. Fig. 3 is a plan view of the rocking mechanism; and Fig. 4 is a side elevation, partly broken away, of the rocker and rocking mechanism.

My invention relates to the class of tilting furnaces, and more particularly to tilting open-hearth steel furnaces. Heretofore furnaces of this tilting type have been supported upon rollers which rest upon curved tracks.

With this construction it is difficult to obtain an even support for the furnace, especially under the expansion and contraction thereof when subjected to heat. Such constructions are, moreover, difficult and expensive to build and to maintain and are structurally poorly adapted for large furnaces.

My invention is designed to provide simple and effective apparatus for supporting, carrying, and tilting furnaces of this type.

In the drawings, 2 represents the furnace proper, which is carried on transverse frames resting on two longitudinal box-girders 3. The transverse frames preferably contain oppositely-inclined girders 4, which are tied together at their inner ends in pairs by gusset plates or girders 5.

The outer ends of the inclined beams 4 are secured to the vertical buck-stays or columns 6, which are tied together across the top of the furnace by beams 7. Short separators 8 are preferably used between the inclined beams 4 along each side. The transverse beams constitute separate frames like the ribs of a vessel and the furnace-plates are secured 45 to them.

Each transverse frame is preferably secured to the longitudinal box-girder 3 by lips 9, which allow a slight movement of the frame longitudinally of the girders to permit expansion and contraction under heat. Each box-girder 3 is of sufficient strength to carry the whole weight of the furnace and does so carry its weight in certain tilted positions. The box-

girders 3 are preferably of fish-belly form, as shown in Fig. 2, and these longitudinal girders rest upon rockers located under their end portions. Each rocker is made up of a pair of curved girders 10, each girder preferably consisting of a steel casting of the form shown in Fig. 1, the intermediate lower portion of the casting being preferably recessed, as shown in Fig. 2, to receive the rail or support 11. These rails 11 form the upper bearing portions of longitudinally-movable beds or supports 12, which are of box-girder form and rest upon rollers 13. The rollers 13 move upon stationary tracks 14, forming part of the foundation. The rollers are arranged in pairs and mounted upon transverse shafts 15, and each roller-shaft extends through a longitudinal casting 16, which ties the set of rollers together.

The intermediate rollers 13 of the set are slightly smaller in diameter than the rollers near the ends of the set to distribute the load 75 and compensate for the deflection of the girder by reason of the heavy load thereon.

Each of the steel castings forming the rockers bears upon oppositely-located rollers 17, mounted in stationary bearings upon tracks 80 18. These rollers 17 are, however, only guide-rollers and do not carry any substantial portion of the load. They serve to compel the rocking or turning of the furnace when the longitudinal bed is moved endwise.

I have shown the longitudinal beds or supports 12 as actuating the rockers by means of racks 19, carried on the beds between the rails 11 and engaging segmental racks 20, located between the castings of each rocker and shown in Figs. 2 and 4. The beds or supports 12 are moved endwise by means of any suitable mechanism, and for this purpose I have shown each hollow box-girder member 12 as provided with an intermediate inner 95 nut 21, which is carried upon trunnions 22, mounted in the sides of the girder. Through this trunnion-nut extends a screw 23, secured to a shaft 24, extending through a thrust-bearing 25 and actuated by slow-motion gearing 26 from an electric motor 27, mounted upon the end portion of the cantilever-beam 28, forming an extension of the bed 12. The screw turns within a closed casing consisting of pipe-sections or hollow castings 29 and 30, 105 whose inner ends are screwed into the end of

the nut. The section 30 is provided with a stuffing-box 31, through which the shaft 24 extends, while the end of the section 29 is closed. This casing is filled with oil which lubricates the screw and nut.

In operating the furnace the electric motors are actuated to turn the screws in either direction desired, and these screws acting through the nuts will move the beds or supports 12 endwise, and thus actuate the rockers through their rack connections. As the beds move endwise the guide-rollers 17 compel the furnace to rock or roll upon its axis.

The advantages of my invention result from supporting the tilting furnace upon longitudinally-moving beds, also from the longitudinally-moving beds in connection with means for holding the furnace in position and causing it to turn as the supports are moved endwise. A simple and efficient structure is thus obtained. The frame arrangement for the furnace distributes the load over the longitudinal girders which transmit it to the rockers. The arrangement for causing endwise movement of the rockers is inclosed and not liable to get out of order while easy access may be had to the various parts.

The turning of the furnace may be secured by link mechanism or other device than the guide-rollers shown, the means for moving the supports endwise may be varied, and the structure of the furnace and actuating mechanism for moving it may be changed without departing from my invention.

35 I claim—

1. A tilting furnace supported upon beds, and mechanism for moving said beds endwise in a plane at an angle to the plane of rotation of the furnace; substantially as described.

40 2. A tilting furnace carried upon longitudinal-movable beds, means for moving the beds in planes at an angle to the plane of rotation of the furnace and mechanism for holding the furnace in position and causing it to turn as the beds are moved longitudinally; substantially as described.

45 3. A tilting furnace carried upon endwise-movable beds, means for moving the beds in planes at an angle to the plane of rotation of the furnace and guiding-rollers arranged to cause turning of the furnace when the beds are moved longitudinally; substantially as described.

50 4. A tilting furnace supported upon curved end rockers, said curved rockers being carried on endwise-movable beds, and mechanism for moving the beds longitudinally; substantially as described.

55 5. A tilting furnace carried upon curved end rockers, endwise-movable beds supporting the rockers, and guide-rollers engaging the rockers to cause tilting of the furnace; substantially as described.

60 6. A tilting furnace carried upon endwise-

movable beams or supports, and horizontal sets of rollers upon which said beams rest; substantially as described.

7. A tilting furnace having end rockers supported upon endwise-movable beams means for moving the beams at an angle to the plane of rotation and gear connections between the rockers and beams; substantially as described.

75 8. A tilting furnace having supporting end rockers, longitudinal beams extending over the rockers and between them and the furnace structure, and transverse surrounding frames for the furnace secured on the longitudinal beams or girders; substantially as described.

80 9. A tilting furnace having supporting end rockers, longitudinal beams extending over the rockers and between them and the furnace structure, and transverse surrounding frames for the furnace secured on the longitudinal beams or girders, each surrounding 85 frame having lower oppositely-inclined beams between the furnace and the longitudinal beams; substantially as described.

90 10. A tilting furnace having oppositely-inclined transverse beams beneath it and longitudinal girders supporting said beams and having a sliding clip connection therewith; substantially as described.

95 11. A tilting furnace having transverse frames supported upon longitudinal girders, 95 curved rockers upon which the longitudinal girders are carried, flat beds supporting the curved rockers, and means for tilting the furnace and bringing the curved rockers to a different position relative to the flat beds; substantially as described.

100 12. A tilting furnace supported upon longitudinal girders, end rockers upon which the girders rest, endwise-movable beds upon which the rockers are supported, and mechanism for moving the beds endwise; substantially as described.

105 13. A tilting furnace having tilting mechanism comprising a curved rocker having toothed connection with a rack, screw-gear 110 arranged to move the rack endwise and an endwise-movable bed on which the rocker is supported; substantially as described.

115 14. A tilting furnace having end rockers, racks having toothed engagement with said rockers and screw-gear arranged to connect the racks; substantially as described.

120 15. A tilting furnace having rockers carried upon hollow box-girders and screw mechanism inclosed within the box-girders and arranged to move them endwise; substantially as described.

125 16. A tilting furnace having a curved rocker carried upon an endwise-movable bed having a trunnioned nut, a screw engaging said nut and means for rotating the screw; substantially as described.

17. A tilting furnace carried upon endwise-

movable box-girders, nuts trunnioned within the box-girders, screws engaging the nuts, an inclosed casing for the screws, said screws having projecting stems and mechanism for 5 rotating said stems; substantially as described.

18. A tilting furnace having curved end rockers supported upon endwise-movable hollow girders, horizontal sets of rollers upon

which the girders rest and screw mechanism 10 within the girders arranged to move them endwise; substantially as described.

In testimony whereof I have hereunto set my hand.
